UNITED STATES PATENT OFFICE.

EDMOND H. SENGER, OF LOS ANGELES, CALIFORNIA.

BODY REST FOR WASHTUBS.

Application filed December 13, 1924. Serial No. 755,706.

This invention relates to and has for a primary object the provision of an improved type of body rest adapted to be removably attached to washtubs, sinks, and the like, for the purpose of relieving the strain on the back during a washing operation.

Another object is to provide an improved body rest for the purpose described, including means for removably attaching the same in position for use on a tub or wash basin and a series of adjustments whereby the elevation and angle of the rest may be adjusted to convenient positions for use.

Another object is to provide means for supporting the body of the operator in the act of washing, and including an adjustable clamping device attachable to the upper edge of the washtub, a second adjustable clamping device attachable to the end of a wash tub and near the bottom thereof, a body rest adjustably supported on said clamping devices and arranged to be moved into selected positions and positioned above the tub whereby during a washing operation said rest may form a support for the body and prevent undue strain on the back.

A still further object is to provide a body rest that will be adjustably supported on a tub and including a plurality of adjustments so arranged that said rest may be universally moved into selected positions for use.

Other objects may appear as the description progresses.

In the accompanying drawing I have shown a preferred embodiment of my invention, subject to modification within the scope of the appended claims without departing from the spirit thereof.

In said drawings:

Fig. 1 is a perspective view of my improved body rest attached to a wash basin of ordinary character in position for use.

Fig. 2 is a horizontal section taken on line 2—2 of Fig. 1.

Fig. 3 is a fragmentary sectional view taken on line 3—3 of Fig. 1, showing the rest adjusting means.

Referring now particularly to Fig. 1, it will be noted that my device embodies as primary elements an upholstered rest A, which is longitudinally adjustable on a pair of standards B, B, an upper clamp C to which said standards are also adjustably connected, and a lower clamping member D to which the lower ends of said standards are also adjustably connected, whereby the same

may be attached to a washtub or basin of usual character as at E.

The rest A has a lug a at each end thereof which is pivotally attached to the upper end of a pair of spaced parallel rods F, F, which are slidable in the standards B, B. The rest A is adjustably pivotally on the rods F, F and may be held in a selected angle by means of a wing nut a' adjacent each of the lugs a, and adapted to be threaded over a screw a² so that when said nuts are tightened the rest will be securely held in a selected position and preferably above the upper edge e of the basin E.

The rest supporting rods F, F are slidably held in a pair of spaced bosses f, f, formed on the upper ends of the standards B, B, the pair of bosses in each case being connected by means of rib portions f' so as to provide an opening between the bosses for the reception of an eye bolt G, one of which encompasses each of the rods F, F and is held in the opening 1, 1 between the lugs f, f.

The stems g, g, of said eye bolts are threaded so as to receive knobs or hand wheels g', g', so that when the rods F, F are moved upwardly or downwardly on the standards B, B, the hand wheels g', g' may be tightened against the portions f', f' of the standards, for the purpose of drawing the eyes G to frictional engagement with the rods F, F for preventing the movement of said rods.

The upper ends of standards B, B are pivotally attached to the clamping member C which overlies the upper edge e of the basin E, a pair of lugs 2, 2, being provided near each end of the member C between which the lower bosses f on the upper ends of the standards B, B are adapted to be held by means of screws 3, 3. A clamping member C' is adjustably mounted on the member C for engagement with the lower side of the flange e of the basin E, as shown. Said member C' has a depending lug 4 on each end thereof, with an extension 5 which is slidably mounted between a pair of spaced ribs 6, 6, integrally formed with the member C and depending therefrom and provided with a boss 7 on the lower end thereof.

One of the bosses 7 and one pair of the ribs 6, 6 are provided on each end of the member C for slidably supporting the adjacent lug 4 of the member C' and an adjusting screw H is threaded into the boss 7 in each case for engagement with the lug 4, whereby the member C' may be forced up

wardly into firm engagement with the flange *e* of the basin when the hand wheels *h*, *h* on said adjusting screws are turned.

The lowermost clamping member *D* is substantially elongated and is composed of two main parts *d* and *d'* which are slidably connected together and adapted to be adjusted longitudinally of each other. The member *d* has an elongated boss 8 formed thereon and an end portion 9 which receives and holds a rod *I*. Said rod is secured at the end of the member *d* by means of a nut 10 and the other end 11 thereof extends substantially through a portion 12 on the member *d'* and substantially beyond the end thereof, and is adapted to receive an elongated nut *N* with wings 13, 13 thereon, whereby when said nut is turned on the rod the member *d'* may be slidably moved on the member *d*.

20 The member *d* also has an elongated boss 14 with portions 15, 15 extended upwardly and outwardly therefrom, and adapted to overlie a longitudinally formed rib 16 formed on the member *d*. Said rib serves to 25 guide the member *d'* on the member *d*. Each of the members *d* and *d'* has a vertically extended rib *r*, *r*, thereon which parallels the rod *I*, and said members also have a transversely disposed block or face plate 17 which 30 is adapted to frictionally engage each end 18 of the basin *E*. Thus, when the nut *N* is threaded inwardly on the rod *I* the block 17 on the member *D* will be frictionally engaged with one of the ends of the basin, 35 while the block 17 on the member *d'* will correspondingly engage the other end of said basin and serve to support the clamping member *D* on the lower portion of said basin.

The lower portions of the standards *B*, *B* 40 are of angular cross section and are provided at their lower extremities with lugs 19, 19 to which are pivotally attached brace members *J*, *J*, by means of bolts 20, 20. The lowermost clamping member *D* has a 45 pair of spaced and depending lugs 21, 21 which are adapted to be adjustably connected with the braces *J*, *J* by means of bolts 22, 22, extended through elongated slots 23, 23 formed in said braces and having wing nuts 24, 24 threaded onto their outer ends for frictionally holding the members *J*, *J* in selected 50 positions with respect to the lugs 21, 21. Thus, as shown in Fig. 1 the device is attached to the basin *E* by means of the clamping members *C* and *D*.

When the device is positioned as shown, the adjusting screws *H*, *H* are operated by means of their hand wheels *h*, *h*, for moving the member *C'* upwardly and the member *C* 60 downwardly against opposite edges of the flange *e* of the basin. Thereafter, the nut *N* may be operated for clamping the blocks or face plates 17, 17 against the ends 18, 18 of the basin, the member *d'* in such case being slidably moved on the member *d*. The 65

elevation of the rest *A* is then determined and the rods *F*, *F* are moved upwardly or downwardly in the bosses *f*, *f*, on the standards *B*, *B*, to a convenient position, whereupon the hand wheels *g'*, *g'* are turned for tightening the eye bolts *G*, *G* and securing said rods in selected position. The body rest *A* may then be adjusted as to its angle on the rods *F*, *F* by loosening and thereafter tightening the nuts *a'* on the upper ends of the rods *F*, *F*.

The angle of the rods *F*, *F* and the position of the rest *A* either inwardly or outwardly of the plane of the flange *e* of the basin may be determined and fixed by loosening the nuts 24, 24 on the clamping member *D* so that the braces *J*, *J* will slide thereover and move the lower ends of the standards *B*, *B* inwardly or outwardly. Thereafter, when said nuts are tightened the standards *B*, *B* of the rods *F*, *F* will be held in fixed position.

When used in connection with a sink the clamping members *C* and *C'* are adapted to engage the upper edge of the sink basin 90 in the same manner as shown in connection with the wash basin in Fig. 1.

Now, it will be observed from the foregoing description and the illustration of my invention in the accompanying drawing, that I have provided a device capable of ready attachment to and detachment from a wash basin or sink, and also capable of universal adjustment for supporting the body rest *A* at a desired angle and elevation most convenient to a person in a washing operation, and the device is generally adapted for use for receiving the weight of the body during a washing operation and preventing undue strain on the back.

What I claim is:

1. In combination with a basin, separate clamping devices attachable to an upper and a lower portion of said basin, a body rest pivotally and slidably mounted on the upper clamping device, and adjustable guide members attached at their upper ends to said body rest and connected at their lower ends with said lower clamping devices for supporting said body rest at selected angles and elevations.

2. In combination with a basin, a pair of elongated clamping members adapted for engagement with the opposite sides of a flange on said basin, a clamping device therebelow adjustable for attachment to basins of different length, and having portions engaging the opposite ends of said basin, standards pivotally mounted on said upper clamping members and adjustably connected with said lower clamping members, and a body rest positioned above said basin and having members slidably held in said standards whereby the angle and elevation of said body rest may be adjusted.

3. In combination with a basin a pair of elongated clamping members adjustably connected for attachment to the upper edge of said basin, a supplementary clamping device therebelow for attachment to the lower portion of said basin, a pair of standards pivotally connected to said upper clamping member and adjustably connected with said lower clamping member, and a body rest supported on said standards, for the purpose described.

4. In combination with a basin a pair of elongated clamping members adjustably connected for attachment to the upper edge of said basin, a supplementary clamping device therebelow for attachment to the lower portion of said basin, a pair of standards pivotally connected to said upper clamping members and adjustably connected with said lower clamping device, a body rest supported on said standards, and means for pivotally adjusting said body rest on said standards.

5. In combination with a basin a pair of elongated clamping members adjustably connected for attachment to the upper edge of said basin, a supplementary clamping device therebelow for attachment to the lower portion of said basin, a pair of standards pivotally connected to said upper clamping members and adjustably connected with said lower clamping device, a body rest supported on said standards, and means for vertically adjusting said body rest on said standards.

6. In combination with a basin a pair of elongated clamping members adjustably connected for attachment to the upper edge of said basin, a supplementary clamping device therebelow for attachment to the lower portion of said basin, a pair of standards pivotally connected to said upper clamping members and adjustably connected with said lower clamping device, a body rest, and means for adjusting and supporting said body rest at different angles and elevations on said standards.

7. In combination with a basin a pair of spaced standards, rods slidably supported therein, means for adjustably supporting said rods in selected positions on said stand-

ards, a body rest carried on said rods, and means for detachably supporting said standards on said basin, for the purpose described.

8. In combination with a basin a pair of spaced standards, rods slidably supported therein, means for adjustably supporting said rods in selected positions on said standards, a body rest carried on said rods, and means for detachably supporting said standards on said basin, said last mentioned means including separate clamping devices attachable to the upper and lower portions of said basin respectively.

9. In combination with a basin a pair of spaced standards, rods slidably supported therein, means for adjustably supporting said rods in selected positions on said standards, a body rest carried on said rods, means for detachably supporting said standards on said basin, said last mentioned means including separate clamping devices attachable to the upper and lower portions of said basin respectively, and means for adjusting the angle of said standards relative to said clamping devices.

10. In combination with a wash basin having a flange thereon, a clamping device including members adjustably connected for gripping opposite sides of said flange, a body rest, means for adjustably supporting the same on said clamping members at different elevations, and supplemental clamping means connected with said body rest for adjusting said rest to different angles.

11. In combination with a wash basin having a flange thereon, a clamping device including members adjustably connected for gripping opposite sides of said flange, a body rest, means for adjustably supporting the same on said clamping members at different elevations, supplemental means for adjusting said rest to different angles, a separate clamping device also attachable to said basin, and adjusting means connected with said rest support and said separate clamping device whereby said rest may be adjusted forwardly or backwardly and held in selected positions relative to the basin.

EDMOND H. SENGER.
